AUTOMATIC BLOWTORCH

Lester L. Lasher, Beachmont, Mass., assignor to
S. C. Brody, Brookline, Mass.

Application November 16, 1929, Serial No. 407,632

6 Claims. (Cl. 158—35)

This invention relates to automatic blow torches, and particularly to an automatic blow torch using alcohol for fuel.

Such torches, as usually constructed, are either 5 (1) of the double barrel type, in which case the pressure cylinder, and the lamp cylinder whose function it is to bathe in flame the gooseneck of the pressure cylinder while the torch is in operation, are constructed as distinct and independent barrels adjustably clamped to each other; or 10 (2) of the single barrel type, in which case both the pressure cylinder and the lamp cylinder are immovably fixed in their proper combinative relation by being built together in a common casing 15 or body unit.

Although both types of torch are well-known in the trade and have been the subject of numerous patents, they are open to the common objection that it is necessary to keep the lamp cylinder constantly lighted and its flame playing directly and continuously on the gooseneck of the pressure cylinder while the torch is in operation in order to generate sufficient pressure in the pressure cylinder to produce the reducing jet at the gooseneck orifice. With each type of torch, therefore, care must be taken that the flame from the lamp cylinder shall at all times and under all conditions and in all positions of use of the torch be continuously played directly on the gooseneck tube 25 in order that the torch may continue to operate.

Where operating conditions are unfavorable, as where the torch must be held in an abnormal position or the work is inconveniently accessible, the flame of the lamp cylinder will not directly play on the gooseneck tube, and the torch will not operate at maximum efficiency. The same is true where the torch is being operated in the open or in a draughty room and hence is necessarily subject to the vagaries of the wind, with the result that the flame from the lamp cylinder is liable to be temporarily blown away from the gooseneck tube or even to be wholly extinguished.

Aside from this disadvantage, however, the automatic blow torch of either type, as heretofore constructed, has been open to the further objection that in its necessity for keeping the lamp cylinder continuously lighted while the torch is at work, a considerable quantity of fuel is consumed. This fuel is contained in the lamp cylinder itself, 50 which must therefore be of sufficient size to serve as a reservoir for an adequate supply of fuel.

Although as a result of this condition, the lamp cylinder of the double-barrel torch is made of generous size, being in fact usually of the same size as the pressure cylinder, and although such

lamp cylinder is capable of adjustment longitudinally of the pressure cylinder, it was not possible to take advantage of the generous size and adjustable character of the lamp cylinder and utilize the lamp cylinder as an extended handle in operating the torch, because of the necessity for keeping the flame end of such cylinder at all times in immediate association with the gooseneck tube of the pressure cylinder. In fact, with the single barrel torch, it is customary to provide the torch with a definite handle as such in order to facilitate manipulating the torch.

In either type of torch, the lamp cylinder was, therefore, an element of but single function, such function being to supply continuously and at all times the heating flame for the gooseneck tube, and in order that it might fulfill this function efficiently it was necessary that the flame end of the lamp cylinder be positioned sufficiently close to the gooseneck as directly to bathe the gooseneck with the heat flame in all positions of use of the torch.

Single barrel torches using gasoline for fuel have been made and sold which could be primed or started by means of a candle or matches, or by providing the torch itself with a priming cup or pan which was adapted to be filled with fuel and lighted in order to start the torch. Such torches, however, are not generally satisfactory, because it is necessary for the user to carry an extra supply of fuel with him in order to fill the priming cup or pan in starting the torch.

To the end therefore of avoiding these several objections to automatic blow torches as heretofore constructed, I have devised my present invention. According to it, I avoid the necessity for keeping the gooseneck tube continuously and directly bathed in the heating flame from the lamp cylinder once the torch is primed and the pressure cylinder delivering its reducing jet.

With my torch, the flame from the lamp cylinder is a priming or starting flame used only when the torch is started rather than a continuously operating heating flame which must be played directly on the gooseneck not only in starting the torch but continuously thereafter so long as the torch is in operation. This permits me to extinguish the priming flame as soon as the torch is started, and thereafter to use the lamp cylinder as an adjustable handle for manipulating the lighted torch, with resultant saving in fuel consumption. Inasmuch as the priming flame may be immediately extinguished once the torch is lighted, all liability of sudden draughts blowing

the heating flame away from the gooseneck or wholly extinguishing the same is avoided.

Moreover, since the priming flame is used only to start the torch and is thereafter extinguished, 5 the large supply of fuel which it is possible to carry in the lamp cylinder constitutes a reserve reservoir which may be drawn upon should the fuel supply in the pressure cylinder become exhausted at an inconvenient occasion.

10 With my torch, therefore the lamp cylinder is an element or unit of triple function in that it is (1) a primer or starter in starting the torch, (2) an extension handle in the subsequent manipulation of the lighted torch, and (3) a reserve reservoir for fuel at all times.

15 The principles of my inventions, are applicable to the several well-known types of automatic blow-torch now on the market, and as illustrative of the many adaptations which may be made, I 20 have shown several characteristic embodiments thereof in the accompanying drawings.

25 Referring to such drawings:

Fig. 1 is an elevation of a double-barreled automatic blow-torch in accordance with my invention, and showing the parts in their priming or starting position.

30 Fig. 2 is a similar view showing the parts in one of the numerous positions to which they may be adjusted after the torch has been primed, the flame of the lamp cylinder having been extinguished and the lamp cylinder being now used as a manipulating handle for the lighted torch.

35 Fig. 3 is an elevation showing only the pressure-generating cylinder and parts carried thereby, the torch being lighted, and this view illustrating graphically the complete independence of the generating cylinder from the lamp cylinder.

40 Fig. 4 is a vertical section through the torch shown in Fig. 1.

Fig. 5 is a cross-section through Fig. 4 on approximately the line 5—5 of Fig. 4.

45 Fig. 6 is a longitudinal section through the burner tube and gooseneck and showing a modification.

50 Fig. 7 is an elevation of a torch of single barrel type modified in accordance with my invention, the adjustable lamp cylinder unit with which such torch may be equipped being shown as adjusted to a position wherein it affords an extended manipulating handle for the lighted torch.

55 Fig. 8 is a vertical section through the torch of Fig. 7 but showing the adjustable lamp cylinder as adjusted to its starting or priming position with reference to the gooseneck tube.

Fig. 9 is a cross section through Fig. 8 on approximately the line 9—9 of Fig. 8.

60 Fig. 10 is an elevation showing a still further possible modification for a torch of the single barrel type, and

Fig. 11 is a vertical section through the torch of Fig. 10.

65 Referring first to the double-barrel type of torch shown in Figs. 1 to 5 inclusive, I have indicated at 1 a lamp cylinder and at 2 a pressure cylinder which are detachably and adjustably connected to each other as at 3 by a spring clamp which permits said barrels to be detached from each other when desired and to be either slid or rotated relative to each other.

70 The lower end of the lamp cylinder 1 is closed by a removable cap 4 and its upper end by a removable cap 5. These caps may be threaded to engage corresponding screw threads formed on the barrel adjacent its ends.

75 The lamp cylinder is filled with fuel through its lower end, and when occasion demands such fuel may be withdrawn at said lower end. The upper end of the barrel is closed by a relatively short section of wick 6 which affords a priming or starting flame.

80 Inasmuch as the wick of the lamp cylinder is ignited only in starting the torch and the starting or priming flame F (Fig. 1) furnished by such wick is thereafter immediately extinguished and remains extinguished during the operation of the torch, the wick 6 need be only a short section, filling only a comparatively trivial portion of the flame cylinder and thus allowing unusual space within the cylinder for the storage of fuel.

85 The lower end of the pressure cylinder 2 is closed by a removable screw cap 7 and this cylinder is filled with fuel through this end. At its upper end, the pressure cylinder is closed by a sleeve cap 8 soldered or otherwise fixed thereto, 90 said cap 8 anchoring the inner end of a gooseneck tube 9.

95 The gooseneck tube 9 is filled with any suitable wicking 10 extending into the fuel in the pressure cylinder, and at its outer end is formed to receive a jet plug 11, having a jet orifice 12 (Fig. 4). The 100 plug 11 may be mounted in the gooseneck in any desired manner, as by the screw threaded connection 13 shown in Fig. 4 wherein the plug is represented as being externally threaded to screw 105 into a corresponding series of internal threads on the gooseneck. Both gooseneck and plug are of some relatively good heat conductive material, as brass. The upper end of the wick 10 of the gooseneck terminates short of the adjacent face 110 of the jet plug 11, affording a vapor space 10a and the jet plug itself is chambered, as indicated at 11a, also to afford a vapor space, the vapor spaces 10a and 11a thus provided permitting the vapor to be pre-heated when the torch is in operation.

115 My invention involves the concept of a burner tube of material of good heat conductivity applied to the outer end of the gooseneck tube 9 in such manner as to afford an uninterrupted heat conductor to the gooseneck tube whereby once 120 the torch is started, a reducing flame R (Figs. 2 and 3) is continuously emitted from the gooseneck even after the starting flame F from the lamp cylinder is extinguished.

125 The burner tube is indicated at 14 and is a simple length of brass or other material of good heat conducting property, perforated as at 15 to assist combustion, and over the wick 6 of the flame cylinder opened as at 16. It is detachably secured at its inner end to the gooseneck in any desired manner. As shown in Figs. 1 to 4, inclusive, the inner end of the burner tube is enlarged as at 17 and sleeved over the outer end of the gooseneck. The sleeve 17 extends well back of the jet orifice 12 of the plug 11 and is internally threaded to engage external threads on the outer end of the gooseneck, as generally indicated at 18.

130 In Fig. 6, I show a modification in which the burner tube 14 and jet plug 11 are formed in one piece, preferably with a hexagonal or otherwise shaped intermediate portion 11a by means of which the unit may be screwed into the gooseneck tube 9.

135 In both this form and the form of Figs. 1 to 5, the unit affords an unbroken or uninterrupted path for the conduction of the heat to a point well beyond the jet orifice of the plug.

140 In both forms, moreover, it will be noted that the operation of screwing the burner tube on or off the gooseneck results in a scraping or cutting

off any deposits of scale which have accumulated on the burner, plug and gooseneck. Such scale are heat-insulating rather than heat-conducting, and unless periodically removed detracts from the efficiency of the torch.

In both forms, however, the torch once primed, will continue to generate pressure and emit the reducing flame R without the necessity of keeping the gooseneck bathed in the starting flame F from the lamp cylinder 1. In fact, the flame F may be extinguished as soon as the torch is lighted, and the lamp cylinder may be wholly disconnected, as indicated in Fig. 3 or slid downwardly on the barrel 2, as shown in Fig. 2 and used as an extension handle for manipulating the lighted torch.

In this latter figure the cap 5 which was removed when the lamp cylinder was lighted to start the torch is shown as having been replaced.

In the form of torch shown in Figs. 7, 8 and 9, the pressure cylinder 19 is of generally oval shape, as is common in this type of torch and closed at top and bottom as shown, but instead of combining in a single unit fuel chambers for both the pressure and lamp cylinder wicks, the barrel 19 is solely a fuel reservoir for the gooseneck wick 20 and the fuel reservoir for the lamp cylinder or starting wick 21 is a separate unit 22, being in fact a duplicate of the lamp cylinder 1 of Figs. 1 to 6 and being adjustably connected with the pressure cylinder 19 by the spring clamp 23. The gooseneck tube is indicated at 24, the jet plug at 25, the burner tube at 26, the removable filling cap for the pressure cylinder 19 at 27 and those for the lamp cylinder 22 at 28 and 29, respectively.

When an even stronger reducing flame is desired than would be furnished by the burner tube operating alone, the priming flame may be adjusted to bathe the lower part of the gooseneck tube in flame, thus generating more pressure by reason of the additional heat which such flame affords at this point.

In this form of torch, the pressure cylinder 19 is longitudinally indented at opposite sides, as indicated at 30 to insure proper grip of the spring clamp 23 and to guide said clamp in its sliding movements longitudinally of the pressure cylinder. The position of the lamp cylinder in starting the torch is shown in Fig. 8 and its position when the torch is lighted, the lamp cylinder wick extinguished and the lamp cylinder used as an extension handle for manipulating the lighted torch is shown in Fig. 7. It will thus be observed that I have dispensed entirely with the provision of any fixed manipulating handle, as such, as is common in a torch of this general type.

Such a fixed handle, however, is shown in the form of torch illustrated in Figs. 10 and 11. In this form of torch, the lamp and pressure reservoirs are associated in a single unit or casing 31 which is partitioned transversely or otherwise, as at 32 to provide a fuel reservoir 33 for the gooseneck wick 34 and a fuel reservoir 35 for the flame wick 36, each reservoir having its own filling plugs 37 and 38 respectively the plug 37 constituting a mounting means for the fixed handle 39.

The flame wick 36 in this form of torch is mounted in a wick holder 40 extending through the fuel chamber 33 and the wick itself is long enough to depend into the fuel chamber 35. The upper end of the wick holder is threaded to receive a closure cap 41.

The gooseneck 42, jet plug 43 and burner tube 44 are of the same general construction as the corresponding parts in the torches of Figs. 1 to 9.

In this type of torch, the wick holder 40 and wick

therein are usually disposed obliquely to the longitudinal axis of the casing 31, this being desirable because of the necessity for bringing the heat flame directly beneath the jet orifice of the gooseneck, but with my novel burner tube attachment such arrangement is not necessary since there is no longer any occasion for continuously playing the heating flame directly on the jet plug while the torch is in operation.

This is indicated graphically in Fig. 10 wherein the flame wick is shown as extinguished after the torch has been started and is projecting the reducing flame R.

The starting position of the torch is shown in Fig. 11.

Although the tube 9 has been referred to as a "gooseneck", this being the usual term employed in the trade to describe such tube, it is obvious that the tube 9 need not be of gooseneck shape, and hence this term as used herein is to be understood as meaning any heat conducting and pressure chamber tube, whether of gooseneck shape or otherwise, within which the fuel is vaporized and pressure generated when sufficiently heated.

Various other modifications in structure and combinative arrangement may obviously be resorted to within the spirit and scope of my invention as defined in the appended claims.

What I therefore claim and desire to secure by Letters Patent is:

1. In an automatic blow torch, a pressure reservoir having a pressure generating tube, a lamp reservoir having a starting wick adapted when lighted to bathe in flame a portion of the pressure generating tube to cause generation of pressure therein and thereafter to be extinguished during the period of operation of the torch, and a combustion burner tube mounted upon said pressure generating tube with its inner end overlapping the discharge end of said pressure generating tube to provide a continuous unbroken path for the conduction of heat from said combustion burner to a point back of the discharge end of said pressure generating tube and effective after combustion occurs in the combustion tube and the lamp wick has been extinguished continuously to produce a reducing flame, and means adjustably connecting said reservoirs whereby the lamp reservoir may be adjusted to a position remote from the combustion tube so as to serve as an extended handle for manipulating the now-generating torch.

2. In an automatic blow torch, a pressure reservoir having a pressure generating tube, a lamp reservoir having a starting wick adapted when lighted to bathe in flame a portion of the pressure generating tube to cause generation of pressure therein and thereafter to be extinguished during the period of operation of the torch, and a combustion burner tube mounted upon said pressure generating tube and effective after combustion occurs in the combustion tube and the lamp wick has been extinguished continuously to produce a reducing flame, and means adjustably connecting said reservoirs whereby the lamp reservoir may be adjusted to a position remote from the combustion tube so as to serve as an extended handle for manipulating the now-generating torch.

3. In an automatic self-generating blow torch, a pressure generating unit comprising a pressure reservoir adapted to contain a liquid fuel, a wick tube extending from said pressure reservoir and having a jet delivery opening, a combustion burner connected to said wick tube, a priming unit comprising a priming reservoir having a wick

therein, said priming unit being detachably and adjustably connected with the pressure generating unit so that said wick may be brought into operative relationship with said wick tube and 5 combustion burner for priming purposes, and said combustion burner having a screw-thread connection with said pressure generating unit whereby after combustion occurs in the combustion burner and the priming unit has been extinguished a reducing flame is produced through the now self-generating torch.

4. In an automatic self-generating blow torch, a pressure generating unit comprising a pressure reservoir adapted to contain a liquid fuel, a wick 15 tube extending from said pressure reservoir and having a jet delivery opening, a combustion burner connected to said wick tube, a priming unit comprising a priming reservoir, said priming unit being detachably and adjustably connected with 20 the pressure generating unit so that said priming unit may be brought into operative relationship with said wick tube and combustion burner and said combustion burner having a connection with said pressure generating unit whereby after com- 25 bustion occurs in the combustion burner and the priming unit has been extinguished a reducing flame is produced through the now self-generating torch.

5. In an automatic self-generating blow torch, 30 a pressure generating unit comprising a pressure reservoir adapted to contain a liquid fuel, a wick tube extending from said pressure reservoir and having a jet delivery opening, a combustion burner connected to said wick tube, a priming unit comprising a priming reservoir having a wick 35

therein, said priming unit being adjustably connected with the pressure generating unit so that said wick may be brought into operative relationship with said wick tube and combustion burner and said combustion burner having a connection with said pressure generating unit which provides a continuous unbroken path for the transmission of heat from said combustion burner to a point back of the jet delivery opening whereby after combustion occurs in the combustion burner and the priming unit has been extinguished a reducing flame is produced through the now self-generating torch.

6. In an automatic self-generating blow torch, a pressure generating unit comprising a pressure reservoir adapted to contain a liquid fuel, a wick tube extending from said pressure reservoir and having a jet delivery opening, a combustion burner connected to said wick tube, a priming unit comprising a priming reservoir, said priming unit being adjustably connected with the pressure generating unit so that said priming unit may be brought into operative relationship with said wick tube and combustion burner for priming purposes and said combustion burner having a connection with said pressure generating unit which provides a continuous unbroken path for the transmission of heat from said combustion burner to a point back of the jet delivery opening whereby after combustion occurs in the combustion burner and the priming unit has been extinguished a reducing flame is produced through the now self-generating torch.
